UNITED STATES PATENT OFFICE.

EDWARD B. CRAFT, OF HACKENSACK, NEW JERSEY, ASSIGNOR TO WESTERN ELECTRIC COMPANY, OF NEW YORK, N. Y., A CORPORATION OF ILLINOIS.

AUTOMATIC TELEPHONE-EXCHANGE SELECTOR.

1,101,684.

Specification of Letters Patent. Patented June 30, 1914.

Application filed February 26, 1912. Serial No. 679,935.

To all whom it may concern:

Be it known that I, EDWARD B. CRAFT, citizen of the United States, residing at Hackensack, in the county of Bergen and State of New Jersey, have invented a certain new and useful Improvement in Automatic Telephone-Exchange Selectors, of which the following is a full, clear, concise, and exact description.

10 This invention relates to automatic switches for effecting the interconnection of telephone lines, and is adapted for use in either automatic or semi-automatic telephone exchange systems.

15 The prime object of this invention is to provide a selector serving a relatively large number of lines wherein any terminal may be reached in a relatively short time by one of a plurality of brushes common to the row without necessitating the provision of a separate electrical brush-choosing switch.

20 In accordance with this invention, the terminals are divided into sections and each section is provided with a brush, and a common movable element is provided, adapted to select the particular brush having access to the section containing the desired terminal and cause it alone to engage the terminals of that section and select the desired line. This may be accomplished in a variety 25 of ways. In the arrangement herein shown, the row of terminals is divided into sections and the brush carrier is common to the entire set of brushes serving the row, a particular brush being rendered active by suitable mechanism to engage the terminals of its section, the remaining brushes being inoperative to engage the terminals they are adapted to serve.

30 The invention is illustrated in connection with a selector of the panel type and the brushes are shown as being loosely mounted upon an elevating rod to which they may be individually coupled by a separate trip rod 35 and elevated by a clutch. The trip rod may be actuated by an electromagnet, which electromagnet may also serve to control the retaining pawl of the brush-elevating rod.

35 Referring to the drawings, Figure 1 is a front elevation of that much of a panel selector necessary to an understanding of the invention; Fig. 2 is an enlarged section on line 2-2 of Fig. 1; Fig. 3 is an enlarged side elevation of what is shown in Fig. 2,

these two views showing the brush selecting mechanism and a portion of the panel; Fig. 4 is a perspective view of the brush selecting mechanism; Fig. 5 is an enlarged view partially in section of the elevating mechanism; Fig. 6 is an enlarged side elevation of the retractive impulse controlling mechanism; Fig. 7 is a section on line 7-7 of Fig. 6, and Fig. 8 is a front view of that part of Fig. 6 showing the interrupter, comprising commutator segments and brushes. 65

The selector shown is capable of serving five hundred lines divided into five horizontal banks of a hundred terminals each, multiplied so as to be accessible to brushes traveling before each of its faces. In order, however, to avoid needless duplication of parts and to give a clearer idea of that part of the structure claimed herein, portions only of two successive banks of line terminals 66 are shown, it being understood that for each 70 of the rows in the three omitted sections of terminals in Fig. 6 a brush carrier 28 with its brushes 29, 30, 31 and 32 is provided. Each individual selector mechanism may comprise high and low speed elevating 75 clutches 75, 76, acting upon the brush elevating rod 25 through a plate 24 rigidly secured thereto, shown in Fig. 6; the brush-elevating rod 25, extending the entire length of the panel; five brush carriers 28, each 80 with three brushes 29, 30, 31, 32, (30 and 31 being in effect one) adapted to contact with the fixed terminals 34, 35 and 36 in their movement, as shown in Fig. 2, when elevated by the rod 25; current-supplying 85 members 29', 30', 32', for the respective brushes 29, 30, 32; a rod 47 for tripping the brushes into engagement with the elevating rod 25; a combined brush-trip and brush-release magnet 45, and an interrupter 57 for 90 the retractive control mechanism.

The brush elevating rod 25 is provided with a notch 49 for each brush carrier 28. These notches are so arranged that counting upwardly in the normal position of the rod 100 they are at successively decreasing heights from the floors 67 of the sections. On the other hand the interlocking fingers 44 of the brush carriage 28 are each equally distant from the floors of the sections when the carriers are at normal. Thus it is possible to select any predetermined brush by raising the brush rod 25 until the interlocking

finger 44 is adjacent its notch 49 in the rod 25, when the rod 47 is given a slight vertical movement by the arm 39 due to the energization of the magnet 45, whereupon the 5 projection 23 on said trip rod causes said finger to move into the adjacent notch, the notch being extended downward longitudinally of the rod to permit the finger to move down into the notch upon continued 10 upward movement of the rod to effectively interlock the same with the rod. By examining the relation of the other notches to their respective fingers at this moment of selection, it will be evident that those below 15 are not in alinement, being above their respective fingers, and those above are not in alinement, being below their respective fingers. The upward movement of the rod may then be continued until the selected 20 brush reaches the desired terminal, where it is held during conversation and thereafter released and restored by gravity, or may be driven back to its normal position. The upward movement of the rod 25 may be 25 caused by contact with the low-speed clutch 76 alone, which is rigidly secured to a constantly rotating shaft 50 or a high-speed clutch 75 rigidly secured to a constantly rotating shaft 53, or both intermittently. 30 These shafts may rotate at the same rate of speed, but due to the differences in diameter of the clutches 75, 76, the rate of speed at which they elevate the brushes is different. The contact of the rod with these 35 clutches may be controlled by any suitable apparatus, that shown being electromagnets 51 and 54 which when energized, cause the plate 24 of the brush rod 25 to engage with their respective clutches and slowly or rapidly elevate the brush rod. The initial movement of said rod may be caused by the energization of the low-speed clutch magnet 51, and at the instant one of the grooves on the brush rod 25 is adjacent the finger 45 of the brush serving the desired hundreds, current is momentarily applied to shift-magnet 45, which acts through the shift arm 39 to give said brush trip rod a slight upward movement causing the corresponding finger 44 to engage with the groove 49 in the brush rod 25 which rod seizes and elevates the brush to the end of the brush selecting range, when the rack 55 engages with the retaining pawl 65. Current is 55 then either maintained applied to the magnet 51 of the low-speed clutch 76 to continue the elevation of the brush rod 25 at low-speed to the desired terminal, or transferred to the magnet 54 of the high speed clutch 60 75 which elevates the brush rod at a relatively higher speed over the tens terminals, when current to the magnet 54 is cut off and again supplied to the magnet 51 shifting the rod 25 from the high speed to the low 65 speed clutch when it is raised again at low

speed until the desired terminal is reached by the brush, where it is held by the pawl 65. When it is desired to restore the mechanism, current is applied to magnet 45 which will cause the pawl 65 to be withdrawn from the rack, whereupon the rod and brush are restored. Current may be supplied to these clutch controlling magnets by means of an interrupter 57 shown in Figs. 6, 7 and 8, the contact arm 58 and metallic segments 59 sending back impulses to a sender or other suitable mechanism by means of which the preliminary movement of the brush rod 25 during brush selection may be controlled, the contact brush 60 and metallic segments 61 sending back impulses by means of which the upward movement of the selected brush over the tens line terminals may be controlled, and the brush 58 serving also with the metallic segments 62 85 to send back impulses by means of which the travel of the brush over the units terminals may be controlled. The brush 63 and the continuous metallic segment 64 supplies return or ground to these circuits. 90

I claim:

1. In a selector, a longitudinally movable shaft, a plurality of brushes normally loosely mounted thereon, a catch carried by each brush, and a plurality of means on said shaft for coöperating with said catches, respectively, whereby any desired brush may be secured to said shaft. 95

2. In a selector, a shaft, a plurality of brushes normally loosely mounted thereon, a catch carried by each brush, a plurality of means on said shaft for coöperating with said catches, respectively, and a device for simultaneously actuating said catches, said means being arranged at successively increasing distances from the normal positions of said catches whereby a single brush may be secured to said shaft at a time. 105

3. In a selector, the combination with a row of terminals divided into sections, a plurality of brushes, one for each section, a brush seizing device, means for coupling said device to the brushes individually, and for moving the selected brush along its respective section of said row. 110

4. In a selector, the combination with a row of terminals divided into sections, a brush for each section, each of said brushes being capable of movement over its respective section independently of the others, a device adapted to individually seize and elevate said brushes, means for giving said brush-seizing device a primary movement to seize a brush, and a secondary movement to cause it to traverse the terminals of its section. 120

5. In a selector, the combination with a row of terminals divided into sections, a brush normally resting at the bottom of each section, a brush-seizing rod normally in- 125

- operative relation to said brushes, and means for causing said rod to individually seize and elevate any one of said brushes over its respective section of said row.
- 5 6. In a selector, the combination with a row of terminals divided into sections, a brush for each section having a finger by which it may be moved, an actuating rod for said brushes having means for interlocking with said fingers individually, and means for causing the selected brush to traverse the terminals of its section.
- 10 7. In a selector, the combination with a row of terminals divided into sections, means for individually seizing said brushes, means for elevating the selected brush to the desired terminal in its section, means for retaining the same thereat, and a magnet adapted to cause the actuation of the brush seizing means and to control said brush-retaining means.
- 15 8. In an automatic switch, a longitudinally movable support, a plurality of sets of brushes normally loosely mounted thereon, and means whereby any desired set of brushes may be temporarily fixed to said support to move therewith.
- 20 9. In an automatic switch, a movable support, a plurality of sets of multiply connected brushes normally loosely mounted thereon, and means whereby any desired brush set may be temporarily locked to said support to move therewith.
- 25 10. In an automatic switch, a bodily displaceable support, a plurality of sets of brushes normally loosely mounted thereon, and means for causing any desired brush set to be temporarily fixed to said support to move therewith.
- 30 40 11. In an automatic switch, a longitudinally movable rod, a plurality of sets of brushes normally loosely mounted thereon, and means for selectively locking said brush sets to said rod to move therewith.
12. In a selector, brushes, a longitudinally movable support therefor, a portion of said support being of magnetic material, a rotatable power member, and an electromagnet adjacent said portion for drawing said support into frictional engagement with said power member.
13. In a selector, the combination with stationary terminals, brushes arranged to traverse said terminals, of a support for said brushes, a plate carried by said support, power members rotatable in the same plane and located on opposite sides of said plate, and electromagnets for selectively causing operative engagement of said plate with either of said power members.
14. In a selector, the combination with rows of stationary terminals and brushes arranged to traverse said rows, of a longitudinally movable rod to which said brushes may be locked, a plate carried by said rod, a rotatable friction disk adjacent said plate, and an electromagnet for drawing said plate into engagement with said friction disk.
15. In a telephone switch, the combination with rows of terminals, brushes therefor, a pair of pulleys, an elevating rod for said brushes in operative relation to said pulleys, means for causing engagement of said rod with either of said pulleys, and means for rotating said pulleys whereby said rod may be moved longitudinally at different rates of speed.

In witness whereof, I, hereunto subscribe my name this 24th day of February A. D., 1912.

EDWARD B. CRAFT.
